BLADE-DISPENSING MAGAZINE

Nicholas Testi, Boston, Mass., assignor to The
Gillette Company, Boston, Mass., a corporation
of Delaware

Application July 29, 1946, Serial No. 686,915

14 Claims. (Cl. 206—16)

1

The present invention relates to magazines for dispensing razor blades.

The problem of providing magazines which will dispense razor blades as needed in an assured and reliable manner becomes increasingly difficult as the thickness of the blades decreases. Thus, the problem of providing a magazine which will reliably dispense unwrapped blades whose thickness is in the order of .007" or less, and particularly the extremely fine flexible double-edged blades commercially known as "thin" blades whose thickness is of the order of only .004", is an especially difficult one. The present invention is addressed to a simple and practical solution of that problem.

One object of the present invention is to provide a simple, compact and inexpensive magazine for dispensing unwrapped blades of .007" thickness or less, which notwithstanding the thinness of the blades, will dispense them in a positive, assured and reliable manner, and without jamming.

Another object of the present invention is to provide a blade-dispensing magazine wherein the blade-ejecting member has means for selecting the end blade from a stack of aligned thin blades and initially advancing it from its original position in said stack, and wherein the security of the driving connection between said blade-ejecting member and said blade is substantially strengthened after said initial advancement.

Another object of the present invention is to provide a magazine which will dispense relatively thin centrally-slotted blades, having a plurality of transversely-extending branch notches communicating with the main central slot, in a longitudinal direction, through engagement of a reciprocable blade-ejecting member with the blade material bordering a predetermined transversely-extending branch notch or notches, the blade-ejecting member being definitely prevented from engaging the blade in the zones of any branch notch other than the desired predetermined correct ones.

Another object of the present invention is to provide a magazine for dispensing relatively thin blades from a stack of such blades housed in the magazine, wherein simple, reliable and stable means are provided for holding back or stripping from the blade being ejected the thin adjacent

2

blades, said means being inherently adapted to function with extreme accuracy and being free of objectionable warping, shrinking or other undesirable stresses or factors, both during as well as after its manufacture, and which, were they present, would tend to impair the accuracy and effectiveness of its functioning.

Another object of the present invention is to provide a magazine having some or all of the foregoing features which can be readily manufactured under the latitude of ordinary ranges of commercial manufacturing tolerances, and which will afford the advantages resulting from said features without requiring adherence during production to any special or critically close tolerances, particularly in the assembly of parts.

Another object of the present invention is to provide a dispensing magazine having the aforementioned unusual advantages and which is yet 20 of relatively simple construction and inexpensive to produce and which readily lends itself to mass production techniques.

With the above and other objects in view, which will appear more fully from the following detailed description, accompanying drawings and appended claims, the present invention in one of its aspects may include, broadly, a magazine containing a stack of aligned relatively thin razor blades, blade-dispensing means including a blade-forwarding member movable into driving relation with the end blade of said stack, said blade-forwarding member itself being provided with means co-operating with said end blade insuring that only that blade of said stack of thin blades will be directly driven forward by said member, and not the adjacent or following blades, and means for improving and substantially strengthening the security of the driving connection between the blade-forwarding member and the forwarded blade after selective displacement of the latter from its position in said stack, thereby affording assured selection and guaranteed secure ejection of only one thin blade at a time from said stack of thin blades, and making that selection and the security of the ejection entirely independent of any critical arrangement or relation between the blade-forwarding member and any other part of said magazine.

The present invention more specifically may include a casing enclosing or containing a stack

of unwrapped aligned blades, spring means for yieldably urging said stack against a fixed element or elements so that at least the forward end of the uppermost or end blade of said stack will be in exit position, a reciprocable blade-forwarding member drivingly engageable solely with said uppermost blade, said member having two portions of invariable or fixed relation to each other, one of said portions being adapted to bear against some portion of the upper surface of said uppermost blade and the other portion extending with respect to said first-mentioned portion in the direction of the thickness of said blade by an amount not exceeding the minimum thickness of said blades and said last-mentioned portion being drivingly engageable with an edge portion of said blade thereby assuring positive initial displacement of only said uppermost blade no matter how thin the blades in said stack may be, and means causing the blade-forwarding member and the blade relatively to shift into more secure engagement with each other after initial displacement of the blade, thereby assuring that the blade-forwarding member will not slip out of operative engagement with the blade during the subsequent ejection of the latter.

The present invention in another of its aspects may include a casing housing a stack of unwrapped aligned blades, the blades being centrally slotted longitudinally and having a plurality of transversely extending branch notches communicating with the central slot, blade-ejection means including a blade-forwarding member reciprocable with respect to said casing in the longitudinal direction of said blades, said blade-forwarding member having a blade-engaging portion adapted to be brought into abutting driving engagement with an edge portion of the blade bordering a predetermined one of said transversely extending branch notches to eject said blade from the magazine in a longitudinal direction, and means holding said blade-engaging portion of said member out of abutting driving engagement with the edge portion of any but the desired predetermined branch notch.

The present invention in still another of its aspects may include a casing housing a stack of aligned unwrapped thin blades, blade-ejection means including a reciprocable blade-forwarding member drivingly engageable solely with the end thin blade of said stack and adapted to slide said blade along a predetermined exit path, and stripping means alongside said path for holding back the next thin blade in said stack during the ejection of the end thin blade including a relatively short flange integral with said casing and extending in parallel spaced relation to a wall thereof into obstructing relation to said next thin blade, said flange being spaced from said wall by an amount less than the combined thickness of the aforementioned two thin blades, but not less than the thickness of one thin blade, thereby providing a gap along said exit path through which only one blade can be passed at a time, the flange serving to obstruct and hold back the blade next to the thin end one, thereby relatively stripping it from the end blade as the latter is forwarded during ejection.

Referring now to the drawings wherein like reference characters indicate like parts:

Figure 1 represents an enlarged perspective view of a loaded blade magazine constituting one illustrative embodiment of the present invention, shown with its slide cover in the closed position;

Fig. 2 represents a perspective view showing

how the magazine of Fig. 1 may be manipulated to eject a blade for subsequent manual placement in the razor; the ejected blade and the magazine slide cover being shown at the end of the forward stroke of the latter;

Fig. 3 represents a perspective view showing the magazine of Fig. 1 operatively associated with a safety razor, with the magazine slide cover being retracted preparatory to feeding a fresh blade directly into the associated razor;

Fig. 4 represents a longitudinal cross-sectional view taken through the center of the blade magazine with retracted slide cover shown in Fig. 3; the razor being omitted for the sake of clarity;

Fig. 5 represents a plan view in slight perspective looking down on the magazine with retracted slide cover shown in Fig. 3; the razor again being omitted for the sake of clarity;

Fig. 6 represents a longitudinal cross-sectional view similar to that of Fig. 4 but showing the blade-ejecting slide cover partially advanced on its forward stroke, and the uppermost blade partially ejected from the magazine;

Fig. 7 represents a transverse cross-sectional view taken on line 7—7 of Fig. 6, looking in the direction of the arrows;

Fig. 8 represents a transverse cross-sectional view taken on line 8—8 of Fig. 6, looking in the direction of the arrows; the magazine slide cover and associated blade-forwarding member being omitted for the sake of clarity;

Fig. 9 represents a fragmentary sectional view taken on line 9—9 of Fig. 8, looking in the direction of the arrows;

Fig. 10 represents a longitudinal cross-sectional view taken on line 10—10 of Fig. 1, looking in the direction of the arrows; and

Fig. 11 represents an exploded view showing the major parts of the magazine of Fig. 1, in perspective, prior to assembly.

Referring now more particularly to Figures 1, 10 and 11, the particular embodiment of the present invention illustrated in the drawings may include a generally tubular casing 1 open at its opposite ends, a blade-carrying base member 2 insertable into said casing, a stack-actuating spring 3, and a reciprocable blade-dispensing slide cover 4. Casing 1 may be constructed of sheet material, as for example sheet aluminum, folded to provide the bottom panel 5, a pair of opposed side panels 6 and 7 and a pair of inwardly-extending blade-exit-path-determining top flanges or panels 8 and 9 having a substantial gap therebetween. If desired, however, the casing may be molded from any suitable thermoplastic material, such as "Lucite" or the like. A pair of inwardly-extending guide-ribs or lugs 10 and 11, which may be struck or pressed from the material of the side panels 6 and 7, may be provided near the forward or dispensing end of the casing, for the purpose of guiding the head of a safety razor into correct operative engagement with the magazine for loading. Immediately below these guide-ribs 10 and 11 may be provided a pair of outwardly-extending stops 12 and 13, which may be pressed from, or molded integrally with, the casing side panels. These stops 12 and 13 extend into abutting relation with the forward edges of the cover side panels 14 and 15, and thus serve to limit the forward movement of the reciprocable slide cover 4.

A pair of inwardly-extending blade-stripping flanges 16 and 17 are also provided near the dispensing end of the casing 1. These flanges 16 and 17, as illustrated in Figs. 8 and 9, may

be struck from the material of the casing side panels 6 and 7, and preferably extend parallel to the casing top panels 8 and 9 spaced therefrom by an amount not less than the thickness of one blade, but not as much as the combined thickness of two blades, so as to permit the passage of only one blade at a time through the gaps between the flanges 16 and 17 and the overlying panels 8 and 9. These blade-stripping ribs 16 and 17, each of which preferably extend inwardly into the magazine for only a relatively short distance, lie in abutting relation to the next to the uppermost and lower blades of the stack, but do not extend into abutting relation to the uppermost blade, thereby permitting said uppermost blade to be ejected from the magazine, and serving to hold back and strip therefrom the next blade immediately adjacent thereto, which might otherwise tend to be carried or dragged along with the uppermost blade through adhesion or friction.

The gaps between the blade-stripping flanges 16 and 17 and the overlying juxtaposed portions of the casing top panels 8 and 9 may be readily and economically formed or created with extreme accuracy by merely bending them inwardly and upwardly around an actual blade of the same thickness as those to be dispensed into the positions shown in Figure 8. In other words, by bending these blade-stripping flanges up into their final positions around a suitable-positioned blade, or wafer of corresponding thickness, and then withdrawing said blade or wafer, gaps will be provided having the desired dimension, as determined by the thickness of the blade or wafer around which the flanges were bent.

The stack-lifting spring 3, which may be bifurcated to provide a pair of upwardly-bowed leg portions 18 and 19, may be permanently secured inside the tubular casing 1 to the bottom panel 5 thereof by any suitable means, as for instance by rivets 20, or by being soldered, spot welded or otherwise fastened thereto.

The blade-carrying base member 2, which may be conveniently molded from thermoplastic material, such as "Lucite" or the like, may include a generally flat panel 21 longitudinally recessed along its under side as at 22 to accommodate the spring 3, and an upwardly-extending rear wall 23 having a special set-back 24 providing a rear stop for limiting the rearward or return movement of slide cover 4 through engagement with the downwardly-extending stop pins 25 thereof. Base member 2 is also provided with a centrally disposed, upwardly extending blade-locating rib 26, which is adapted to extend upwardly through the center slots of a stack of slotted blades 27, and thus position or locate the blades in a horizontal sense and in vertical alignment on the base member 2. The upper edge of this blade-locating rib 26 is especially shaped, for reasons which will subsequently appear. Blade-retarding portions 28, extending not quite up to the top of the rib 26, may be provided on opposite sides of the rib near its forward end for the purpose of preventing longitudinal shifting of all the blades except the uppermost one, by occupying the vertically-aligned diamond-shaped openings near the forward ends thereof, as illustrated in Fig. 5. The base member 2 may also be provided with a pair of upstanding integral stop posts 29 for limiting the insertion of the razor head into the mouth of the magazine, as illustrated more particularly in Fig. 3 of the drawings. Concav-

ities or recesses 30 may also be provided on opposite side edges of the base member 2, and after the magazine parts have been assembled, the juxtaposed portions 31 of the casing side panels 7 and 8 may be pressed or crimped thereto into to hold the magazine parts assembled.

Elongated spring-accommodating longitudinal slots 32 may be provided in the base member 2 on opposite sides of the central blade-locating rib 26, in order to permit the forward ends of the stack-actuating spring arms 18 and 19 to extend through the base member 2 and against the lowermost blade of the stack 27, thereby operatively to press upwardly against the stack.

The blades of the stack 27 may be of the double-edge type, as shown in the drawings, and preferably are of thickness not exceeding approximately .007". The thickness of the blades has been considerably exaggerated in the drawings for the sake of clarity. Thus, for example, the magazine in the drawings has been illustrated as containing only seven blades, together occupying a relatively substantial amount of space inside the magazine. It is to be understood, however, that in actual practice a magazine having the general dimensions of the one illustrated in the drawings may readily accommodate as many as twenty or twenty-five blades of .007" thickness or less. Such blades, and particularly the extremely flexible blades of wafer-thinness, about .004" thick, now being sold commercially, may be called thin, or relatively thin, blades; and it is therefore to be understood that these words "thin" or "relatively thin" where used in the specification and claims is intended to signify blades of thickness not exceeding approximately .007", more or less, and particularly the aforementioned extremely flexible wafer-thin blades of thickness in the order of approximately .004".

The slide cover 4 may be provided at or near its forward end with downwardly-dependant side panels 14 and 15, and inturned bottom panels or flanges 33 and 34, to embrace the casing 1 and thus permit the slide cover 4 to be reciprocated to-and-fro along that casing between the limits defined by the forward stops 12 and 13, and the rear stop 24. A blade-feeding element, which may be in the form of a leaf spring 35, may be secured to the slide cover 4 in any suitable manner, as for example, by rivets 36. The front end of leaf spring 35 is preferably curved downwardly as at 37, and presents the forward tip thereof for driving engagement with the blades of the stack 27. A central notch 38 may be provided in the front end of the feeder spring 35, into which may extend the upper edge of the blade-locating rib 26. Blade-driving projections 39, constituting the most forwardly and downwardly projecting portions of the feeder spring 35, may be disposed adjacent and on opposite sides of the notch 38. The feeder portions adjacent these blade-driving projections 39 are preferably recessed or set back with respect to the tips of the projections 39 in a vertical sense (i. e. in the direction of the thickness of the blades) by a slight amount, not exceeding the thickness of the thin blades that are to be dispensed, as at 40. When the slide cover 4 has been fully retracted to the limit permitted by the engagement of the stop elements 25 and 24, these setback surfaces or shoulders 40 rest on the upper surface of the uppermost blade on opposite sides of and straddling the last transversely-extend-

ing blade-notches 42, and thus gauge or limit the extent to which the blade-driving feeder projections 39 project downwardly into said lateral notches 42. Since these surfaces 40 are set back relative to the tips of the blade-driving projections 39 by an amount not exceeding the thickness of one blade, the projections are thereby prevented from coming into abutting driving relation with the second or underlying blades of the stack, thus insuring that only the uppermost blade will be directly driven forward on the forward stroke of the slide cover 4.

Inclined blade-accommodating notches 41 are also preferably provided at the feeder tip intermediate the blade-engaging surfaces 40 and the blade-driving projections 39, in order to permit improvement in the security of the driving connection between the projections 39 and the forward edges of the transversely-extending blade-notch 42 during transverse flexure or bowing of the rearmost portion of the blade in the course of its ejection.

Downwardly projecting stack-depressing protuberances 43, disposed on opposite sides of the longitudinal center line of the slide cover 4, may be pressed out of the material of said cover, these protuberances serving to depress at least the front ends of the stack of blades 27 against the influence of the stack spring 3, in the manner more particularly illustrated in Fig. 10, when the slide cover 4 is in the closed position shown in Fig. 1. This depression brings the uppermost blade of the stack into abutting relation with the flanges 16 and 17, rendering it impossible for that or the other blades to be even partially ejected when the cover is in closed position. This "securing" of blades against unintended longitudinal movement is also aided by the fact that the upstanding portions 28 of the base member 2 also extend completely through the uppermost blade of the stack on depression of the front stack end by the slide cover protuberances 43; and by the obstruction to forward movement presented by the rear edge of the central rib 26, at least with respect to the lower blades of the stack.

Referring now more particularly to Figure 11, the above-described blade magazine may be readily and easily assembled by dropping the blades of the stack 27 onto the upper surface of the base member 2, so that the central blade-locating rib 26 extends upwardly through the longitudinal slots of the blades, thus holding the blades in vertical alignment. The slide cover 4 may then be telescoped over the casing 1 until the front edges of the cover side panels 14 and 15 respectively encounter the outwardly extending casing stops 12 and 13. The blade-loaded base member 2 may then be inserted into the rear (right) end of the tubular casing 1. As the base member 2 progresses into the casing 1, the legs 18 and 19 of the stack-actuating spring 3 will first be depressed into close proximity to the casing bottom panel 5, and will then be freed and spring upwardly through the base slots 32 into operative contact with the stack 27, lifting said stack up to the position shown in Fig. 10. The casing side walls may then be crimped inwardly as at 31 to project into interlocking engagement with the base concavities 30 (Figs. 3 and 8) thereby effectively locking the magazine parts together.

The hereinabove described magazine may be manipulated to dispense the thin razor blades contained therein in the following manner. The

user, holding the ends of the magazine casing and base portions between the thumb and index or second finger of the left hand as illustrated in Figure 2, grasps the slide cover 4 between the thumb and index or second finger of the right hand placed over the outwardly extending protuberances 44, and then retracts the cover 4 by sliding it to the right as far as it will go, as determined by engagement of the stop pins 25 with the stop surface 24 shown in Figure 4. During most of this rearward movement of slide cover 4, the tips 39 of the feeder spring 35 are held above and clear of the uppermost blade of the stack 27 through the lifting of the front end of the spring against its inherent resilience, caused by the sliding engagement between the upper edge of the blade-locating rib 26 and the uppermost wall of the feeder notch 38. Near the end of the rearward movement, the feeder spring is permitted to lower its tip down onto the upper surface of the uppermost blade, by reason of the downward curvature of the rearmost portion of the upper edge of the rib 26. This upper edge is so curved as to let the spring tip down into the blade-driving position shown in Figures 3, 4 and 5, wherein the spring shoulders 40 rest on the upper surface of the uppermost blade straddling the rearmost transversely-extending pair of blade notches 42, with the blade-driving projections 39 of the feeder spring extending down into said notches 42 and lying in abutting relation with the forward edges 45 of said blade notches 42, on opposite sides of the longitudinal blade slot. The slide cover 4 is then advanced, causing the forward edges of the spring feeder projections 39 first to abut against the aforesaid blade edges 45 in line contact, and thereafter pushingly to slide the uppermost blade forwardly. Since the blade-driving spring projections 39 project downwardly below the blade-surface-abutting shoulders or setback surfaces 40 only by an amount not exceeding the thickness of one blade, solely the uppermost blade of the stack will be directly driven forward by said projections. Any tendency that the second blade in the stack might have to drag or slide forwardly along with the uppermost blade is overcome, as will be seen from Figures 5, 8 and 9, by the presence of the casing flanges 16 and 17 which extend inwardly into the front cut-out corner portions of the blades 27 and lie in abutting relation to the second and underlying blades of the stack. These flanges 16 and 17 thus hold back said second blade and relatively strip it from the uppermost one as the latter is being slid forwardly during ejection.

Coming back to Figures 4, 6 and 7, it will be observed that the uppermost edge of the centrally disposed blade-locating rib 26 is appreciably higher than the under-surface of the casing top flanges 8 and 9, against which the blade being ejected is slidingly held under the influence of the stack-actuating spring legs 18 and 19 acting through the stack of blades. Therefore, as the uppermost blade is slid forward, its central solid end portion 46 rides up over the crest of the rib 26, flexing the blade transversely. This transverse bowing or flexing of the trailing end of the uppermost blade during ejection, which is clearly illustrated in Figs. 6 and 7, greatly improves the security of the initial driving connection between the spring projections 39 and the blade-notch edges 45. Thus, because of this transverse bowing or flexing of the blade during ejection, the blade-notch edges 45 are caused to incline and

shift upwardly on the driving spring-projections 39 into firm, interlocking engagement, since this movement of the blade-notch edges 45 is upwardly in a direction away from and opposite the disengagement direction. This cocking or tilting of the blade-notch edges 45 is facilitated and accommodated by the presence of the inclined spring notches 41 at the tip of the spring between the shoulders 40 and driving projections 39. Thus, these inclined notches 41 accommodate the blade during its transverse flexure or bowing, and contribute to the improvement of the security of the driving engagement between the spring projections 39 and the abutting blade-edges 45 during blade ejection. This transverse bowing of the blade during ejection is of considerable advantage in the dispensing of thin blades wherein the initial selective engagement of the blade-forwarding means with the blade is limited by the extreme thinness of the blade itself. Thus, were it not for the transverse flexure or bowing of the thin blade during ejection, the application of the unavoidable frictional load to the blade during ejection, and particularly where the blade is being slid directly into a razor head, would in many instances cause the blade-engaging driving means to slip upwardly out of driving engagement with the extremely thin blade edge. However, by means of the above-described transverse flexure or bowing of the blade, the blade itself is stiffened in a longitudinal sense, and the thin edges by which the blade is initially selectively advanced shift into more secure and interlocking engagement with respect to the driving projections. The bowing of the blade and the shifting of its driven edges 45 also permit the driving projections 39 to extend completely through, and project beyond the under side of, the blade being expelled from the magazine. It will be noted that the upper surfaces of the blade-driving spring projections 39 are inclined rearwardly and that the under surfaces of these projections are substantially horizontal. The intersection of the horizontal under surface with the rearwardly inclined upper surface forms an acute angle providing a fairly sharp line at the very tip of each driving projection 39, thus insuring sharp line contact with the thin blade edges 45 during the initial selection and forwarding of the uppermost blade of the stack. This sharp line contact affords slip-free driving engagement between projections 39 and blade edges 45 during the initial phase of blade ejection, and is later followed by the cocking or upward tilting of blade edges 45 into more secure interlocking engagement with the driving projections 39 as the trailing end of the blade is bowed upwardly during ejection, as described hereinabove. The slope of the upper surface of the spring projections 39 aids materially in guiding blade edges 45 into the aforesaid more secure interlocking engagement with the spring projections 39, since the cocked blade edges 45 are thereby caused to ride upwardly and rearwardly on the projections 39; and the greater the driving thrust between feeder spring and blade, the more securely and firmly interlocked they become.

The feeder spring 35 can only engage with the edges of the predetermined correct rearmost notches 42 of the blade, because of the presence of the spring-lifting upper edge of blade-locating rib 26. If, for example, through inadvertence, slide cover 4 is not entirely retracted before it is started on its forward stroke, the spring pro-

jections 39 will not have been lowered into engagement with any part of the uppermost blade, and the latter will, therefore, not move forward at all. This feature avoids unintended partial or incomplete ejection of a blade.

In Figure 3 of the drawings, the magazine has been shown operatively associated with a head of a razor of special construction permitting the ready withdrawal or discharge of used blades. This razor is shown in greater detail, and is claimed, in applicant's co-pending application Ser. No. 696,990, filed September 14, 1946. It is to be understood, however, that the magazine of the present invention may be used to load directly any of a large variety of razors intended or designed to receive blades fed endwise longitudinally into an end of the razor head. Thus, for example, the magazine of the present invention may, in some instances with only slight modification, and in other instances without any modification whatsoever, be used to load the razors shown in U. S. Patents Nos. 2,377,388 dated June 5, 1945; 2,299,416, dated October 20, 1942; 1,953,685, dated April 3, 1934; and in applicant's co-pending application Ser. No. 564,770, filed November 23, 1944, now Patent No. 2,424,260. The magazine of the present invention may also be used to dispense double-edged blades that are open at one end, as shown for example in U. S. Patent No. 2,361,512, dated October 31, 1944, and when loaded with such blades may be operatively engaged with, and feed such blades directly into, safety razors designed to receive open-ended blades fed endwise longitudinally therewith, as shown, for example, in the last-mentioned patent.

The magazine of the present invention may also be used, if desired, to dispense blades into the hand of the user (as illustrated in Fig. 2) for subsequent manual placement within the safety razor. When operated in this manner, just before the end of the forward stroke of slide cover 4, the rearmost end 46 of the blade being ejected which was formerly bowed or flexed upwardly by the presence of the upstanding blade-locating rib 26, unbows or straightens itself out as it passes beyond the front end of rib 26, and, under the now unopposed influence of spring 35 acting in combination with the flanges 16 and 17, assumes a reverse downwardly-bowed or downwardly-flexed position. This downward dishing of the blade in the vicinity of its notches 42 snaps the notch forward edges 45 downwardly out of driving engagement with the spring projections 39, whereupon the blade ceases to be moved forward, and spring 35 completes its forward stroke idly. This brings the various blade and magazine parts into the positions illustrated in Figure 2, which clearly shows the tip of the spring 35 pressing down centrally on the upper surface of the blade. Therefore, at the end of the forward stroke of slide cover 4, the blade almost completely projects beyond the magazine and is frictionally lightly held in that position and prevented from falling out by feeder spring 35 pressing downwardly at its central end zone against the upward thrusts exerted by the stationary casing flanges 16 and 17 which then underlie the blade at its opposite side end zones. The projecting blade may then be readily grasped by the user and withdrawn completely from the magazine, against the light pressure exerted by spring 35, without subjecting his fingers to any danger of being cut by the sharp longitudinal edges of the blade.

If, however, the blade is fed directly into the

safety-razor head, as illustrated for example in Fig. 3, the tip of feeder spring 35 and the blade edges 45 will not shift out of driving engagement, but will instead remain in firmly interlocked driving engagement throughout the entire forward stroke of slide cover 4, thus driving the blade fully into the razor head. This occurs because the convex lower or guard blade-clamping surface of the razor head supports the trailing end of the blade being dispensed and thus prevents it from being bowed downwardly by spring 35 after it passes beyond the rib 26.

An unusual feature of the present invention is the provision of a simple compact magazine which will dispense even the very thinnest of razor blades, one by one as needed, in an assured and reliable and jam-free manner, and which yet does not require and is entirely independent of any critically careful assembly of parts to very close tolerances such as would render the magazine impractical for purposes of mass production. Thus, referring to the detailed construction and arrangement of the parts of the illustrated embodiment of the present invention, it will be observed that the base member 2 bears no critical relation to the casing 1; and small variations, for example, in the vertical location of the casing top flanges 8 and 9 with respect to the base 2 in different magazines will be readily accommodated by the resilient stack-actuating spring 3, which will always lift the stack of blades and hold the uppermost blade in its correct exit position against the under side of the flanges 8 and 9 irrespective of the precise vertical distance between these top flanges and the base. Similarly, the slide cover 4 bears no critical relation to the base 2, or casing 1, or the thin blades 27, when assembled, since the blade-ejecting member 35 vertically adjusts itself to the uppermost blade in the stack, and will assuredly select and drive forward only that uppermost blade, due to the predetermined fixed relationship of the spring portions 39 and 40. This relationship can be readily controlled within the required limits of accuracy since both portions 39 and 40 are located on the same single element, namely the vertically-adjustable spring 35. Thus also, the blade-stripping flanges 16 and 17 which strip or hold back the second and underlying blades are integral with the casing walls, and may therefore readily be bent to provide small correctly-dimensioned gaps along the exit path of the uppermost blade just large enough to pass one thin blade, but not large enough to simultaneously pass two such blades, therethrough. Here again the gap widths are determined by and dependent upon the relative positions of portions of the same member, which may easily be controlled within the required limits of accuracy, and without involving establishment of or adherence to any special critical relation between assembled parts.

It will be understood of course that various modifications may be made in the illustrated embodiment without losing the special advantages resulting therefrom, and without departing from the scope of the invention. Thus, for example, the stripping flanges 16 and 17 may be accurately located with respect to the overlying top flanges 8 and 9 by molding casing 1, instead of forming it from sheet material bent into desired form. In either case, however, the gap dimensions will be independent of any relation between assembled separate parts; and the relative shortness of the flanges 16 and 17 avoids unintended undesirable

changes in gap widths, as from warping, shrinkage or expansion, after formation.

If desired, the tip of the feeder spring 35 may, with slight modification, be altered so that the 5 blade-driving projections 39 thereof will drivingly engage the rearmost external edge of the blade 27, instead of engaging the internal notch edges 45 as shown. It will be understood therefore that where reference is made in the claims to a 10 blade "edge" it is intended, unless otherwise clearly indicated, to signify any transversely extending edge of the blade, be it an internal notch edge or an external blade edge.

Thus also, if desired, the casing guide ribs 10 and 11 may be respectively combined with the stripping flanges 16 and 17 into single composite flanges, which will perform the dual functions of guiding the razor head into operative telescoping engagement in the mouth of the magazine, and of stripping the underlying from the uppermost blade during ejection of the latter.

Although the stack-depressing protuberances 43 of the slide-cover 4 are shown near the forward end of the cover, these protuberances may, if desired, extend rearwardly along the major portion of the said cover. Also, the blade-retarding portions 28 of the base member 2 may be dispensed with, if desired, since the combination of the blade-stripping flanges 16 and 17 and the central 20 blade-locating rib 26 will be adequate in the assembled devices to hold back the underlying blades, particularly in view of the progressive depression of the blade stack 27 by the slide-cover protuberances 43.

In another alternative form, the magazine of the present invention may be provided with a special rib or other hand-grip on the under side of the casing for the user's left hand, as indicated for example in the magazine of applicant's prior Patent No. 2,384,503, dated September 11, 1945, for convenience in ejecting a blade for subsequent manual placement into the razor. The slide cover 4 may also be modified, if desired, so as to be grasped near or at its rearmost end, instead of near its foremost end as illustrated; and furthermore the cover, instead of embracing the casing, may slide in slots extending along the top or upper side wall portions of the casing, thus permitting the user to grasp the casing directly by its side walls with the left hand.

Although the magazine of the present invention is particularly advantageous for the dispensing of thin or relatively thin flexible blades, unusual features and advantages thereof may be utilized in the dispensing of relatively thicker more rigid blades, as for example single-edged "Valet" blades of from .0010" to .0012" in thickness as shown in application Serial No. 594,275, filed May 17, 1945, now Patent No. 2,536,109.

Having thus disclosed my invention and described in detail an illustrative embodiment thereof, I claim as new and desire to secure by Letters Patent:

1. In a magazine for dispensing thin flexible blades, stack-locating means for holding a stack of such blades in a predetermined position in said magazine, reciprocable blade-advancing means having a blade-driving projection extending in the direction of the thickness of said blades and shoulder-means engageable with the surface of the end blade of said stack for positioning said projection so that its tip lies in abutting relation to an edge of said end blade, and means for transversely flexing the advancing end blade after its initial displacement, the blade-advancing means

being recessed intermediate its aforesaid blade-driving projection and its shoulder-means to accommodate the transverse flexure of the blade.

2. A blade-dispensing magazine including a casing having a blade-exit passageway, a stack of relatively thin flexible blades in said casing, spring means resiliently urging said stack of blades into position wherein the end blade is in alignment with said blade-exit passageway, blade-dispensing means reciprocable with respect to said casing including a blade-driving portion movable into abutting relation with an edge of said end blade, a blade-engaging stop-shoulder set back from the tip of said driving portion in the direction of the thickness of said blades by an amount not exceeding the thickness of one blade, and blade-flexing means transversely flexing said blade in the region of its engagement by said driving portion during movement of said blade through said blade-exit passageway.

3. In a magazine for dispensing thin flexible blades, stack-locating means for holding a stack of such blades in registration in a predetermined position in such magazine, reciprocable blade-advancing means having an inclined blade-driving projection extending both forwardly and in the direction of the thickness of said blades and shoulder-means having a blade-contacting surface horizontally offset relative to the forward tip of said projection and engageable with the surface of the end blade of said stack for positioning said inclined projection so that its forward tip is in abutment with an edge wall of said end blade, thereby on the initial advancement of said projection selectively to advance said end blade, and a blade-deflecting member located in the path of the thus-advanced blade shifting at least a portion of said edge wall up over the tip of the inclined projection during the blade discharge, thereby to increase the security of the driving engagement after the initial selective advance of the blade.

4. In a magazine for dispensing thin flexible centrally apertured blades, a central blade-locating rib for holding a stack of such blades in registration in a pre-determined position in said magazine, reciprocable blade-advancing means having a blade-driving projection extending in the direction of the thickness of said blades and a set-back shoulder offset laterally with respect to said blade-driving projection and engageable with the surface of the end blade of said stack for positioning said projection to extend only partially into a centrally-located aperture of said blade in abutting relation to an edge wall thereof, thereby on the initial advancement of said blade-advancing means selectively to advance said end blade, said rib serving as a deflection member located in the path of the thus-advanced blade shifting said edge wall in the aforesaid direction during blade discharge to cause the said projection to extend completely through and beyond said centrally-located aperture.

5. In a magazine for dispensing thin flexible blades, stack-locating means for holding a stack of such blades in registration in a predetermined position in said magazine, reciprocable blade-advancing means having a blade-driving element movable in the direction of the thickness of said blades into driving engagement with a transversely medial edge portion of the end blade of said stack and shoulder means engageable with the surface of the end blade of the stack spaced laterally relative to said blade-driving element for positioning the latter in driving relation to the

aforesaid edge portion and a deflection member located in the path of the advancing blade relatively to shift the engaged portions of said driving element and said end blade into more secure driving relation once the blade has been started on its way out.

6. In a magazine for dispensing double-edged blades of the kind having a longitudinal central slot and a plurality of transversely extending notches communicating with said slot, a casing, a central blade-locating panel adapted to extend through the longitudinal slots of a stack of such blades and hold them in substantial registration, a blade-forwarding member reciprocable with respect to said casing in the longitudinal direction of said blades and movable towards and away from said stack in the direction of the thickness of said blades and yieldingly biased towards said panel, said member having a blade-driving portion extending in the said thickness direction of said blades and drivingly abuttable against a predetermined transverse notch edge of the end blade of said stack, the outermost edge of said blade-locating panel projecting through and beyond said end blade and including a downwardly sloped portion and constituting a guide for said yieldingly biased blade-forwarding member adapted to lead the blade-driving portion thereof into operative abutment with said notch edge as aforesaid.

7. In a magazine for dispensing thin longitudinally-slotted double-edged blades, having a casing and a central blade-locating member adapted to extend through the longitudinal slots of a stack of such blades and hold them in substantial registration, a blade-forwarding spring member reciprocable with respect to said casing in the longitudinal direction of said blades and capable of flexing towards and away from said stack in the direction of the thickness of said blades, said spring member having at its outermost tip a pair of blade-driving projections disposed one on either side of the central plane of said blade-locating member and extending in the said thickness direction and abuttable against transverse edge portions of the end blade of said stack, and a pair of blade-surface-engaging shoulders set back with respect to the blade-driving projections in the said thickness direction by an amount not exceeding the thickness of a single blade.

8. In a magazine for dispensing thin longitudinally-slotted double-edged blades, having a casing and a central blade-locating member adapted to extend through the longitudinal slots of a stack of such blades and hold them in substantial registration, a blade-forwarding member reciprocable with respect to said casing in the longitudinal direction of said blades and also movable towards and away from said stack in the direction of the thickness of said blades, said blade-forwarding member having a pair of blade-driving portions extending in the said thickness direction and abuttable against transverse edge portions of the end blade of said stack on opposite sides of the longitudinal axis thereof, and another portion set back relative to said blade-driving portions and movable into surface engagement with said end blade to prevent said blade-driving portions from coming into abutment with any of the other blades of said stack.

9. A magazine for dispensing double-edged long-slot blades of thickness not exceeding .007 inch including a casing adapted to house a stack of such blades, said casing having an upper wall, a blade-locating rib adapted to extend

through the blade slots and hold them in registration; spring means adapted resiliently to urge said stack into predetermined position against said upper casing wall, the casing having a blade-exit passageway defined, at least in part, by said upper casing wall, and a pair of underlying inwardly-extending flanges integral with and extending parallel to said wall within the confines of the casing and each spaced from said upper wall by an amount not less than the thickness of a single blade thereby providing therewith a discharge gap bounded on opposite faces by parallel integral elements, said flanges each adapted to extend into abutting relation to the end of the second blade of said stack, said blade-locating rib extending upwardly at least to the level of the upper surface of said underlying flanges.

10. A container for the dispensing of double-edged blades of thickness not exceeding .007" and having central slots with transverse enlargements, said container including a blade-enclosing member having a sheet metal cover slidably connected therewith, said cover having downwardly and inwardly turned marginal portions embracing portions of the sides of the blade-enclosing member and the latter having stop surfaces in abutting relation to forwardly and rearwardly faced portions of said cover and fixing the path of sliding movement thereof, said blade-enclosing member including a base portion molded of thermoplastic material and having an integral upstanding blade-locating rib transversely-centered therein and adapted to extend through the blade slots to hold the blades in vertically aligned stack formation, said rib including transversely-extending side portions adapted to project into transverse enlargements of the blade slots thereby to hold the blades engaged therewith against longitudinal movement, and an arched multi-pronged spring member in the blade-enclosing member for pressing the blade stack upwardly towards the slidable cover, the cover including a pair of transversely-spaced downwardly-extending projections adapted, when the cover has been fully retracted, to engage edge portions of the uppermost blade in the stack equi-distantly from the blade center line, said cover also including a region adjacent and integral with said projections and engageable with the top surface of the uppermost blade, said projections extending downwardly from said blade-surface-contacting region a distance no greater than the thickness of the blade, whereby the leading end portion of the uppermost blade in the stack will be advanced from said blade-enclosing member as the cover is returned from its retracted position to its container-closing position.

11. A container according to claim 10 wherein the cover further includes a depressed blade-contacting region extending downwardly on opposite sides of the blade center line sufficiently to maintain the uppermost blade in the stack in operative engagement with the transversely-extending side portions of the upstanding blade-locating rib when the cover is in its container-closing position, and said depressed cover region being movable on the retraction of said cover to a position freeing said blade to be lifted by said spring member out of engagement with said side portions, whereby said uppermost blade will be freed for subsequent longitudinal movement by said cover in its return from its retracted position to its container-closing position.

12. A container for the dispensing of double-edged blades of thickness not exceeding .007" and having central slots with side enlargements, said container including a blade-enclosing member having a sheet metal cover slidably connected therewith, said cover having downwardly and inwardly turned marginal portions embracing portions of the sides of the blade-enclosing member and the latter having stop surfaces in abutting relation to forwardly and rearwardly faced portions of said cover and limiting the path of sliding movement thereof, said blade-enclosing member including a base portion having an integral upstanding blade-locating rib transversely centered therein and adapted to extend through the blade slots to hold the blades in vertically aligned stack formation, said rib including blade-retarding side portions adapted to project into side enlargements of the blade slots thereby to hold the blades engaged therewith against longitudinal movement, and a bowed spring member in the blade-enclosing member for pressing the blade stack upwardly towards the slidable cover, the cover having a depressed blade-contacting region extending downwardly on opposite sides of the blade center line sufficiently to maintain the uppermost blade of the stack at a level below the top of said blade-retarding side portions so that said blade will be engaged with said side portions when the cover is closed, thereby to prevent longitudinal blade movement when the cover is in that position, and said depressed cover region being movable on the retraction of said cover to a position freeing said blade for lifting by said spring to a level higher than the top of the blade-retarding side portions of the blade-locating rib, thereby to permit subsequent longitudinal movement of said blade, and projections on said cover engageable with a transverse edge of said blade for driving the blade longitudinally forward as the cover is returned from its retracted position to its container-closing position.

13. A blade magazine including a casing and a stack of relatively thin double-edged long-slotted blades therein, said casing having an upper wall, a blade-locating rib extending through the slotted blades and holding them in registration, spring means resiliently urging said stack against said upper wall, the casing having a blade exit passageway defined, at least in part, by said upper wall and an underlying inwardly extending short flange within the confines of the casing integral with and extending parallel to said upper wall and spaced therefrom by an amount not less than the thickness of a single blade, thereby to provide therewith a discharge gap bounded on opposite faces by parallel integral elements, said flange extending into abutting relation to the end of the second blade of the stack, and said blade-locating rib extending upwardly at least to the level of the upper surface of said underlying flange.

14. A blade magazine including a casing and a stack of relatively thin double-edged long-slotted blades therein, said casing having an upper wall made of metal, a blade-locating rib extending through the slotted blades and holding them in registration, spring means resiliently urging said stack against said upper wall, the casing having a blade exit passageway defined, at least in part, by said upper wall and an underlying inwardly extending short flange within the confines of the casing integral at its one end with and extending parallel to said upper wall and being free at its other end, said flange being struck and bent

from the material of said upper wall and being spaced therefrom by an amount not less than the thickness of a single blade, thereby to provide therewith a discharge gap bounded on opposite faces by parallel integral metal elements, said flange extending into abutting relation to the end of the second blade of the stack, and said blade-locating rib extending upwardly at least to the level of the upper surface of said underlying flange.
